DESIGN FOR A JIG-SAW, CARD, AND FORTUNE GAME DEVICE

Louis P. Bambaci, Harrison, N. Y.

Application March 30, 1935, Serial No. 56,130

Term of patent 7 years

To all whom it may concern:

Be it known that I, Louis P. Bambaci, a citizen of the United States, residing at Harrison, in the county of Westchester and State of New York, have invented a new, original, and ornamental Design for a Jig-Saw, Card, and Fortune Game Device, of which the following is a specification, reference being had to the accompanying drawing, forming part thereof.

Fig. 1 is a face view of a jig-saw, card and fortune game device showing my new design.

Fig. 2 is a side view of the same.

I claim:

The ornamental design for a jig-saw, card and fortune game device as shown.

In testimony whereof I have affixed my signature.

LOUIS P. BAMBACI.
